VACUUM-BOTTLE SUPPORT.

1,143,172.

Specification of Letters Patent. Patented June 15, 1915.

Application filed September 16, 1913. Serial No. 790,098.

To all whom it may concern:

Be it known that I, FREDERICK E. CARLSON, a citizen of the United States, and a resident of New Britain, in the county of 5 Hartford and State of Connecticut, have invented certain new and useful Improvements in Vacuum-Bottle Supports, of which the following is a specification.

This invention relates to a support for the 10 walls of a vacuum bottle embodying features of novelty and advantage.

In the drawings—Figure 1 is a sectional side view. The vacuum bottle is equipped with a support made in accordance with my 15 invention. Fig. 2 is a sectional view on a line 2—2 of Fig. 1. Fig. 3 is a perspective view of the support.

Referring to the drawings *a*, *b*, denotes the walls of the bottle, which is of usual construction, the walls being connected at the neck and requiring a support at or near the bottom to hold them rigid to prevent breakage.

My invention is concerned with the construction of the support which comprises a strip of spring metal 5, the ends of which are folded over upon itself to form clips 6, 6, in which are secured the ends of strips 7, 7, of material which is a non-conductor of heat.

In the manufacture of vacuum bottles, it is quite impossible to prevent slight variations in the distances between the walls, necessitating a careful fitting of supports so as to properly brace the walls. By this invention it is possible to readily produce a support of proper thickness by winding about the clips as much of the strips 7 as may be needed to fill the space between the two walls. Any additional amount over that 40 required can be readily torn or cut off. If

desired, two strips can be secured in each clip giving a double thickness and producing the same results. It is to be noted that as these supports are manufactured ready for use, the strips are not folded around the 45 ends, and just enough is to be folded onto the ends, at the time a support is to be fitted into place, as will act as an effective support between the two walls of the bottle. It has been customary to use sheet asbestos for the 50 strips which are wound about the clips.

The connecting bar between the clips has a light spring action and permits of such slight distortion as may be necessary to fit the support in place, and then tends to assist 55 in holding it in position.

I claim as my invention:

1. A support for the walls of a vacuum insulated vessel comprising a metallic clip formed by bending a strip of metal upon 60 itself, and a sheet of heat-non-conducting material wound about said clip with an end secured therein.

2. A support for the walls of a vacuum insulated vessel comprising a pair of clips 65 connected by a resilient bar and a strip of heat-non-conducting material, secured in each clip and adapted to be wound thereabout.

3. A support for the walls of a vacuum 70 insulated vessel comprising a resilient bar and a strip of heat-non-conducting material secured at each end of said bar and adapted to be wound thereabout to a greater or less extent.

FREDERICK E. CARLSON.
